P. G. EMERY,
SHADE HOLDING MECHANISM,
APPLICATION FILED SEPT. 10, 1904.

1,108,559.

Patented Aug. 25, 1914.

UNITED STATES PATENT OFFICE.

PLATO G. EMERY, OF CHICAGO, ILLINOIS.

SHADE-HOLDING MECHANISM.

1,108,559.

Specification of Letters Patent. Patented Aug. 25, 1914.

Application filed September 19, 1904. Serial No. 225,027.

To all whom it may concern:

Be it known that I, PLATO G. EMERY, a citizen of the United States, residing at Chicago, in the county of Cook and State of Illinois, have invented new and useful Improvements in Shade-Holding Mechanism, of which the following is a specification.

This invention relates to that class of curtain fixtures in which the friction and anti-friction devices are both normally in contact with the frame.

The object of the invention is to provide a simple and inexpensive mechanism which can be readily applied and operated for holding the curtain against its upward tendency and for guiding it evenly in its movement.

In the accompanying drawings Figure 1 illustrates the invention partly in section and 20 shows a portion of the curtain. Figs. 2-6, inclusive, illustrate other embodiments of the invention.

Referring to the drawings, 10 is a hollow shade stick carried by a curtain 11 which is mounted upon a spring-actuated shade roller (not shown) or other suitable means for giving the curtain a constant upward tendency. The shank 12 of the guide 13 is arranged in the end of the stick and a rod 14 is screw-threaded or otherwise connected to the shank at one end and provided with a pendant pinch handle 15 at its other end. A spring 16 within the stick operates to press the guide outward into contact with the frame 7 of the window, door, or other opening in which the curtain travels, and this spring may be arranged in the manner shown in Figs. 1 and 5 or in any other suitable manner.

40 The guide may be cast in one piece or formed out of sheet metal and in the preferred construction illustrated in Fig. 1, it is made hollow throughout its length for lightness. A lever arm 17 is pivotally mounted on a pin 18 in each end of the guide and these arms carry anti-friction rollers 19.

The rollers 19 are held constantly in contact with the frame by an elastic or yielding presser device which is shown in Fig. 1 in the form of a single flat spring 20 loosely arranged in the guide with its ends acting upon the rear ends of the levers 17. This spring may be fastened in the guide if found desirable.

55 It is customary to employ the same mech-

anism at each end of the stick and it will be sufficient to illustrate and describe a single complete mechanism at one end of the stick, as shown in Fig. 1. I do not consider it necessary, however, that the holding mechanism at both ends of the stick should be alike.

In Fig. 2 I have shown two springs 21, as the full equivalent of the single spring 20 in Fig. 1, and they are fastened to the guide at the back thereof. In Fig. 3 the two springs 22 act on the lever arms 23 in front of their pivots. In Fig. 4 the lever arms 24 are pivoted at 25 on the outside of the guide and are acted upon by springs 26 also fastened to the guide on the outer side thereof. In Fig. 5 the anti-friction rollers are carried by a frame 27 provided with a shank 28, arranged within the guide, and acted upon by spring 29. In Fig. 6 the axles 30 of the rollers are arranged in transverse slots 31 in the sides of the guide so that the rollers and the guide may move relatively and bodily, and springs 32 are fastened to the back of the guide and bear against the axles of the rollers.

In all of the several embodiments of the invention which I have illustrated in the drawings the anti-friction devices are elastically mounted on and are movable relative to the guide, being constantly pressed outward by a yielding presser device.

Provision is preferably made for limiting the inward movement (toward the pinch handles) of the anti-friction devices to prevent the fixture from being tilted out of the frame. This is conveniently accomplished by arranging the antifriction devices so that they will engage a part of the guide in their inward movement. In Figs. 1 and 2 the lever arms carrying the antifriction rollers will engage the back wall of the guide at 17'; in Fig. 3 the lever arms will engage the back wall at 23'; in Fig. 5 the frame 27 will engage the back wall 27'; and in Fig. 6 the spring arms 32 will engage the back wall at 32'.

The face 33 of the guide constitutes the friction device of the mechanism and is pressed by the spring (16 in Fig. 1 and 34 in Fig. 5) into frictional contact with the frame to hold the curtain against its upward tendency. The springs acting on the friction devices and the anti-friction devices are independent of each other and these devices

are relatively movable so that the friction devices can be withdrawn from contact with the frame without affecting the anti-friction devices which normally remain constantly in contact with the frame. This withdrawal of the friction devices is accomplished by pressure applied to the pendant handle in the usual manner.

Without limiting myself to the exact construction and arrangement of parts herein shown and described, what I claim and desire to secure by Letters Patent is:—

1. A shade holding mechanism comprising a stick, an elongated guiding element at the end of the stick to frictionally engage the window frame and guide the shade in its movement, means for pressing the guiding element outward, anti-friction devices adjacent to the ends of said guiding element, and an element separate from the means pressing the guiding element for pressing said devices outward in the direction of the length of the stick, one of said elements being constructed to limit inward movement of said devices relatively to said guiding element.

2. A shade holding mechanism comprising a stick, a combined guide and friction device at the end of the stick to frictionally engage a window frame, means for pressing said combined guide and friction device outward, antifriction devices carried by said device and having a limited movement relative thereto, the inward movement of said anti-friction devices being limited by engagement with the combined guide and friction device, and other means independent of said combined guide and friction device pressing means, for pressing the anti-friction devices outward in the direction of the length of the stick.

3. A shade holding mechanism comprising a stick, an elongated guide at the end of the stick to frictionally engage a window frame, and anti-friction devices elastically mounted on the friction-guide at the ends thereof to move inwardly and outwardly in the direction of the length of the stick, said friction-guide being constructed to limit the elastic movement of said anti-friction devices inwardly.

4. A shade holding mechanism comprising a stick, an elongated guide at the end of the stick to frictionally engage a window frame, and anti-friction devices mounted elastically to swing on the friction-guide at the ends thereof, said friction-guide being

constructed to limit the swinging movement of said anti-friction devices inwardly.

5. A shade holding mechanism comprising a stick, an elongated guide at the end of the stick to frictionally engage a window frame, anti-friction rollers mounted to swing on the friction-guide at the ends thereof and having a limited movement relative thereto, said friction-guide being constructed to limit the swinging movement of said anti-friction devices inwardly, and means for pressing said devices outward.

6. A shade holding mechanism comprising a stick, an elongated guide at the end of the stick to frictionally engage a window frame, means for pressing the friction-guide outward, anti-friction devices at the ends of the friction-guide and having a limited movement relative thereto, said friction-guide being constructed to limit the inward movement of said anti-friction devices, and yielding means for pressing said devices outward.

7. A shade holding mechanism comprising a stick, an elongated guide at the end of the stick to frictionally engage a window frame, yielding means for pressing said friction-guide outward, anti-friction devices at the ends of the friction-guide and having a limited movement relative thereto, said friction-guide being constructed to limit the inward movement of said anti-friction devices, and yielding means for pressing said devices outward.

8. A shade holding mechanism comprising a stick, an elongated friction guide at the end of the stick, arms adjacent to the ends of said guide and pivotally mounted thereon, means for imparting a limited inward movement of said arms relative to said guide, anti-friction devices carried by said arms at the ends of the guide, and springs acting upon said arms to press the anti-friction devices outward.

9. A shade holding mechanism comprising a stick, a guide at the end of the stick, rigid lever arms adjacent to the ends of said guide and pivotally mounted thereon, anti-friction rollers on the outer ends of said arms, and springs acting inward on the inner ends of said arms to press the rollers outward.

PLATO G. EMERY.
